CONCRETE BRIDGE PIER AND PIER FOUNDATION

Filed Dec. 21, 1927

FIG. 1.

FIG. 2.

FIG. 3.

C.A.P.TURNER,
Inventor

By *Willard Eddy*,
Attorney

UNITED STATES PATENT OFFICE.

CLAUDE A. P. TURNER, OF MINNEAPOLIS, MINNESOTA.

CONCRETE BRIDGE PIER AND PIER FOUNDATION.

Application filed December 21, 1927. Serial No. 241,649.

My invention relates in general to that class of concrete bridge piers and pier foundations which, like those of my Letters Patent No. 1,563,676, are commonly sunk in deep water 5 through mud or quicksand to hard bottom by the open dredge method. It relates especially to that class of these foundations which are floated to position before completion and are righted by ballast while afloat and while being sunk. It is a main object of the invention to utilize water ballast in building foundations of this class, and at the same time to attain economy, speed and convenience in placing and building structures of this class. To accomplish these objects I incorporate in my improved pier and pier foundation as an integral part thereof a concrete tubular shell, substantially cylindrical, armed with a cutting shoe, and having coaxial inner and outer 10 walls with a plurality of pockets for temporary ballast between the walls.

In the accompanying drawings, illustrating the best manner in which I have contemplated applying the principles of the invention, Fig. 1 is a side elevation of a typical pier consisting of twin piers and foundations which are singly constructed in accordance with these principles and are braced together. Fig. 2 is an incomplete side elevation of one of these 15 twin piers and foundations, partly in vertical axial section. Fig. 3 is a horizontal cross section on the section line 3—3 of Fig. 2.

To build and locate my improved pier and pier foundation in individual form I first provide a unitary base portion thereof which is shown in section in Fig. 2. This base portion, which is to become an integral part of the completed structure, is a hollow columnar concrete casting, is long enough to extend at 20 one and the same time into the air above the water and into the soil below, and is adapted to right itself to a vertical position when afloat. It is towed to position while partly submerged and while supported by its water 25 displacement. It is a tubular shell, substantially cylindrical, open from end to end, and double-walled, comprising the outer wall 2 and the inner wall 3. These walls are coaxial with the central dredging passage 6, and are 30 united at the bottom of the shell in a sharp circular edge armed with the annular cutting shoe 7. In the shown specimen of the invention this shell is reinforced by a suitable steel frame 1 imbedded therein, comprising truss 35 bracing encased in concrete partitions 4, by

which the space between the walls is uniformly divided into a series, or endless train, of ballast pockets 5 which individually reach from the bottom to the top of the shell. These concrete partitions, which are omitted from Fig. 2 for the sake of clarity, are plainly seen in Fig. 3. The lower end portion of the outer wall 2 is larger around than its upper portion and is united therewith by an intermediate frustum-like portion 8, which tapers upward 40 from the section line 3—3, as shown in Fig. 2; while the inner wall 3 has its upper and principal portion cylindrical, and its bottom portion 9 flaring, like an inverted funnel. Alternate pockets 5 may be filled with concrete, and the rest of the pockets may be loaded temporarily with water ballast by siphons, sea-cocks, or other means. Weighted by the contents of these pockets, which are shown empty in the drawings, the shell, after 45 being towed to position and anchored there, naturally sinks through the water and forces the cutting shoe 7 into the soft bottom. During this sinking of the structure its tendency to list in any direction from its vertical position is curbed and counteracted by the resistance of earthy material within and against the flaring portion 9 of the dredging passage 6—a force which arises from the inertia of that material. The sinking of the structure 50 is further controlled and its tendency to list in any direction is resisted, as occasion may require, by selectively varying from time to time the amount of water ballast in the several pockets 5, and by distributing the same 55 mainly to that side of the shell which encounters for the time being the chief resistance to sinking. Dredging may be carried on through the central passage 6 in the usual manner, as with clamshell or orangepeel buckets, 60 while the sinking continues, and until the cutting shoe 7 reaches firm material. Meanwhile the described shell is continued upward by concrete additions integrally united therewith at the top of the shell. Then the soft or 65 loose material is cleaned from the flaring inner surface 9, and the bottom of the dredging passage is sealed, as with a treenail or with concrete deposited through the water by flat-bottom buckets to the sufficient depth of several feet. The structure is then unwatered 70 and the laitance and inferior top stratum of the contained concrete, if any, are removed from the dredging passage. The partly 75 filled and the empty ballast pockets 5 and the 80

dredging pocket 6 are then filled up to the top of the pier with concrete, wherein rock may be imbedded if desired.

I claim as my invention—

- 5 In a structure of a specified class a tubular shell comprising two coaxial walls armed with a cutting shoe and having a plurality of ballast pockets between the walls, the inner wall being flaring at the bottom and substan-

tially cylindrical above, and the outer wall 10 having a substantially cylindrical upper portion, a substantially cylindrical bottom portion and an intermediate frustum-like portion.

Witness my signature at Minneapolis, 15
Minn., December 16th, 1927.
